UNITED STATES PATENT OFFICE.

JOHN NUHN AND FREDERICK KUEHNE, OF JERSEY CITY, NEW JERSEY.

ELASTIC LABEL.

SPECIFICATION forming part of Letters Patent No. 281,391, dated July 17, 1883.

Application filed March 29, 1883. (No model.)

To all whom it may concern:

Be it known that we, JOHN NUHN and FREDERICK KUEHNE, citizens of the United States, and residents of Jersey City, in the county of 5 Hudson and State of New Jersey, have invented certain new and useful Improvements in Elastic Labels, of which the following is a specification.

Our invention relates to a new and improved 10 label for bottles, jugs, &c.; and it consists of a strip of metal bent into circular form and possessing sufficient resiliency to closely fit the neck of the bottle or jug when placed upon the same, as will more fully hereinafter appear, 15 due reference being had to the accompanying drawings, wherein—

Figure 1 represents the blank of the label before the same has been bent into shape; Fig. 2, a view of the same when bent into 20 shape, and Fig. 3 a view of the blank applied to the neck of a bottle.

Tags or labels have been applied to bottles in various ways—for example, by suspending the tag from the neck of the bottle by a chain 25 or tape—and a tag having a rubber eye adapted to be slipped over the neck of the bottle has been employed; but these tags are inconvenient when pouring out the contents of the bottle, and the tags are liable to be slipped around 30 the bottle out of sight.

Our invention is designed to furnish a neat, 35 cheap, and durable tag or label that shall be free from these objections and that can be easily and readily applied to or detached from the bottle or jug; and to this end we construct

our tag or label as follows: We cut from sheet metal a blank of the shape shown in Fig. 1, or of any desired shape sufficiently long to nearly encircle the neck of an ordinary-sized bottle, and bend the same into circular form. The 40 sheet metal composing the label or tag should possess sufficient resiliency to cause the bent blank to retain its circular form under all ordinary circumstances. The tag has the desired word, symbol, or ornament painted, printed, 45 or otherwise affixed to the same, and may be readily attached to any ordinary-sized bottle, jug, or other similar vessel by simply forcing apart the ends of the metallic tag or label and slipping the same around the neck of the vessel, when the resiliency of the metal will instantly cause the tag to firmly clasp the vessel and retain the same securely in place. The tag may also be forced over the top of the bottle 50 onto the neck, if desired.

Having thus described our invention, what 55 we claim is—

The bottle-label formed from the shield or crescent-shaped metal blank into a substantially open spring-ring and bearing a suitable 60 inscription, substantially as described.

Signed at New York city, in the county of New York and State of New York, this 28th day of March, A. D. 1883.

JOHN NUHN.
FREDERICK KUEHNE.
